UNITED STATES PATENT OFFICE.

JOHN R. ARMSTRONG, OF CRANSTON, RHODE ISLAND.

DESIGN FOR A WASHER.

56,847.

Specification for Design.

Patented Jan. 4, 1921.

Application filed April 2, 1920. Serial No. 370,887. Term of patent 14 years.

To all whom it may concern:

Be it known that I, JOHN R. ARMSTRONG, a citizen of the United States, residing at Cranston, county of Providence, State of Rhode Island, have invented a new, original, and ornamental Design for a Washer, of which the following is a specification, reference being had to the accompanying drawing, forming a part thereof.

In said drawing:

Figures 1 and 2 are perspective views of the device taken from opposite sides.

I claim—

The ornamental design for a washer, substantially as shown.

JOHN R. ARMSTRONG.
